UNITED STATES PATENT OFFICE.

JAY H. HALL, OF CLEVELAND, OHIO, ASSIGNOR TO ELECTRIC CONTROLLER AND SUPPLY COMPANY, OF CLEVELAND, OHIO, A CORPORATION OF OHIO.

CONTROLLING SYSTEM FOR ELECTRIC MOTORS.

No. 902,396.

Specification of Letters Patent.

Patented Oct. 27, 1908.

Application filed March 13, 1906. Serial No. 305,746.

To all whom it may concern:

Be it known that I, JAY H. HALL, a citizen of the United States, residing at Cleveland, in the county of Cuyahoga and State of Ohio, 5 have invented or discovered new and useful Improvements in Controlling Systems for Electric Motors, of which the following is a specification.

My invention relates to systems for controlling electric motors from a point distant from them, the motor and rheostat connections being effected by switches which are preferably closed by electro-magnets and opened by springs or weights.

15 It is one object of my invention to provide a system in which but a single wire or conductor will be required between the master-controller and the magnetically-operated controller which controls the motor and 20 rheostat circuits.

It is another object of my invention to provide a magnetically-operated reversing-mechanism, which, when the master-controller has been thrown to the off-position, 25 remains inactive or in the position, to which it was last thrown.

It is also an object of my invention to confine the arcing to only one of a series of switches, which control the rheostat, this 30 provision requiring but a single blow-out magnet.

My system, therefore, applies to the arrangement of the connections of the master and magnetic controller, and the principal 35 rheostat switch, that is, the switch to which the arcing is confined. Beyond this a great variety of systems may be employed for cutting out the speed-controlling resistance to bring the motor or motors with safety up to 40 the required speed. The master-controller may be variously constructed; the magnetic, or principal, controller may embody widely different apparatus; and the rheostatic connections may be variously made, while still 45 retaining the spirit of my invention.

Referring to the drawings which accompany this specification and form a part hereof, Figure 1 is a diagrammatical view showing one form of my invention; Fig. 2, a second form of my invention, differing from the first form in the type of motor reversing mechanism; Fig. 3, a third form of my invention; Fig. 4, a fourth form of my invention; Fig. 5, a fifth form of my invention

showing its application to a multiple unit 55 system; Fig. 6, a sixth form of my invention wherin two relay windings are used; and Fig. 7, a seventh form of my invention, the same being substantially the system shown in Fig. 6 but applied to a multiple train unit 60 system.

Referring to Fig. 1, S¹, S², S³, and S⁴ represent a series of switches thrown in successively by automatic acceleration in accordance with the principles of Patent No. 772,277 65 granted to Arthur C. Eastwood. These switches are shown having their contacts connected with different sections of the resistance R in the manner shown in said patent.

The resistance R is connected to one terminal of the field F' of the motor, the other terminal being connected to the switches S⁴ and S⁵, which, together with the switches S⁷ and S⁸, are preferably like the switches S¹ to S⁴. The switch S⁵ is connected to the negative main; the switches S², S³, and S⁴, to the wire connecting the resistance section R¹ to the contact of the switch S¹; and the switches S⁷ and S⁸, to the positive main. The contacts of the switches S⁵ and S⁶ are connected to the brush A¹ of the armature M of the motor; and of switches S⁶ and S⁷, to the other brush A² of the motor. It will thus be seen that the motor circuit is open at three different groups of contacts, one at the switches S¹ to S⁴, one at the switches S⁶ and S⁷; and one at the switches S⁵ and S⁸. The switches S⁵ and S⁶ operate in pairs alternately with the pair of switches S¹ and S⁴, one pair causing the rotation of the motor in one direction and the other pair, in the opposite direction. The first member of each pair closes first and controls the closing of the second member of the pair. The second member of each pair controls the switch S¹. Each switch is closed by a solenoid, whose core is connected thereto; and opened by springs, as in said Patent No. 772,277.

Supposing the switch B to be closed, the switches S¹ to S⁴ to be open as shown on Fig. 1, and the master-controller G to be moved onto the positive contact G¹, the current flows from the said contact, through the master-controller and the coil of the relay C¹ to a point between the solenoids of the switches S⁵ and S⁶; thence through the solenoid of the switch S⁵ to negative pole of the switch B.

The closing of the switch S^5 closes the contact connected to the brush A^1 and bridges a pair of contacts, one leading to a point between the solenoids of the switches S^6 and S^8 and to one of the pair of contacts of the switch S^6 and the other to a point between the switches S^7 and S^8 and to the second of said pair of contacts of the switch S^6 . The closing of the switch S^5 , therefore, permits current from the master-controller to pass its pair of contacts and through the solenoid of the switch S^7 to the negative main, causing the latter switch to close the connection to the brush A^2 . The closing of the switch S^7 also bridges its pair of contacts, one being connected to one of the contacts of the switch S^8 and to the winding of the solenoid of the switch S^4 , the other contact being connected to the negative main.

20 The energization of the relay C^1 closes its switch C^2 upon the contact of the solenoid of the switch, whereby current from the pole or contact G^1 passes through the winding of the relay C^1 , the switch C^2 , the winding of the 25 solenoid of the switch S^1 , the pair of contacts of the switches S^7 to the negative main through the switch B . This circuit closes the switch S^1 , so that the resistance R , the field F^1 , and the armature M are all in series 30 as follows: from the positive pole of the switch B through the switch S^7 , the brush A^2 , the armature M , the brush A^1 , the switch S^6 , the field F^1 , the whole of the resistance R , and the switch S^1 to the negative pole of the 35 switch B . This circuit necessitates a rotation of the armature in one direction. If the master-controller had closed the controller circuit through the negative pole G^2 , the switches S^6 and S^8 would have been closed instead of the switches S^6 and S^7 , because the current from the positive pole of the switch B would pass first through the solenoid of the switch S^6 and thence through the relay C^1 and the master-controller G to the negative 40 pole G^2 . The closing of the switch S^6 closes its pair of contacts which connects the solenoid of the switch S^8 just as the closing of the pair of contacts of the switch S^6 connects the solenoid of the switch S^7 into the circuit of 45 the master-controller circuit. The pair of the contacts of the switch S^6 will be closed by the switch S^8 whereby the solenoid of the switch S^1 will be included in the master-controller circuit through the switch C^2 , as was 50 the case when the switch S^7 was closed. The motor circuit with the controller G on the pole G^2 is thus traced: from the positive pole of the switch B , through the switch S^6 , the brush A^1 , the armature M , the brush A^2 , 55 the switch S^6 , the field F , the resistance R , and the switch S^1 to the negative pole of the switch B . It will be seen that the movement of the master-controller from the pole G^1 to the pole G^2 has not reversed the flow of 60 current through the motor field F^1 , but has

reversed the flow through the armature, causing a reversal of the rotation of the latter.

The closing of the switch S^4 closes a pair of contacts, one being connected to the positive pole of the switch B and the other through 7 to the winding of the solenoid of the switch S^2 to the contact of the latter switch. The switches S^2 and S^3 each have a pair of contacts, like that of the switch S^1 , one being connected to the positive pole of the switch, 7 and the other being connected through the solenoid of the succeeding switch to the main contact of the said succeeding switch. The last switch S^4 is without a pair of contacts, its solenoid being joined to its own 8 contact.

The switches S^1 to S^4 will close successively and automatically as the acceleration of the motor rises in a manner well known in the art.

If the handle G be thrown from the positive pole G^1 to its center position, as shown on Fig. 1, the relay C^1 is deenergized, causing the switch C^2 to open the circuit of the solenoid of the switch S^1 , thus interrupting the 9 motor circuit. Current still flows equally through the solenoids of the switches S^6 and S^8 , and also equally through the solenoids of the switches S^7 and S^8 ; but since the switches S^6 and S^7 are closed, the air-gap in the magnetic circuits of their operating solenoids is smaller than in the case in switches S^6 and S^8 and therefore, the switches S^6 and S^7 remain closed.

If the controller handle G is again thrown 1 from off-position to the contact G^1 , the switch S^1 is again closed through the switch C^2 and the motor starts as before without any movement of the reversing switches S^6 to S^8 .

If, however, the handle G is thrown to the pole G^2 , both ends of the coil of switch S^6 will be connected to the negative main, while one end of the coil of switch S^8 will be connected to the positive main and the other to the negative main; thus causing the switch S^6 to close and S^8 to open. As soon as the switch S^6 closes, the solenoid of the switch S^8 is placed in the master-controller circuit and that of the switch S^7 is shunted, causing the switch S^8 to close and S^7 to open. The switches S^1 to S^4 are closed as when the controller G was on the pole G^1 , but the armature connections of the motor being reversed, as hereinbefore explained, the armature has its direction of rotation reversed.

It is seen that a motor can be reversed, the circuit thereof always being opened on one switch, this being accomplished by using a single-wire between the master and magnetic or reversing controllers. As the motor circuit always opens at the switch S^1 only the one blow-out magnet is employed, this being designated by the letter O .

In order to prevent the switches S^6 and S^8 , or the switches S^7 and S^8 , closing at the same

time, I employ the interlocking bars t^1 , which are shown diagrammatically, their function being well known as may be seen from Patents Nos. 770,631 and 786,635, granted to

5. Arthur C. Eastwood.

Referring now to Fig. 2, m and n represent two solenoids connected in series across the line. The master-controller circuit is from the handle G , through the relay C^1 and 10 the point o between the solenoids m and n . If the handle G is on the positive contact G^1 , the current from o will traverse the solenoid m to the negative pole of the switch B . In a manner well known, the solenoid m causes 15 the operation of the reverser so that the contact fingers shall move onto the left hand contact strips as shown. As soon as the contact fingers are as shown, the current from the controller G will pass through the relay 20 switch C^2 , which has been closed by the relay magnet C^1 , thence through the solenoid of the switch S^1 , and the contacts s^1 and y^1 to the negative pole of the switch. The energization of the solenoid of the switch S^1 25 closes the said switch, whereby the resistance R is all connected to the negative pole of the switch B . The circuits of the two motors F and F' are now closed, the circuits being in parallel between the points 1 and 2. 30 The circuit of the motor F is thus: from the positive pole of the switch B , through the point 1, the contact fingers L and A^3 , the brush A^2 , the armature M , the brush A^1 , the contact fingers A^4 and F^2 , the field coils F^1 of 35 the motor, the resistance R , and the switch S^1 to the negative pole of the switch B .

The circuit through the motor F' is as follows: from the point 1 passed by the circuit of the motor F through the contact fingers 40 LL and AA^4 , the brush AA^1 , the armature M^1 , the brush AA^2 , the contact fingers AA^3 and FF^2 , and the field FF^1 of the motor F' to the point o where it connects with the return circuit of the motor F .

45 If the handle G is now thrown to off position, the contacts of the reverser will not change as the coils m and n will be equally magnetized. If the handle G is then closed on the negative pole G^2 , the solenoid n will be 50 energized, the circuit thereof being traced thus: from the positive pole of the switch B through the solenoid n , the point o , the relay magnet C^1 , and the handle G to the pole G^2 . The solenoid n , now having an excess of current over the solenoid m , will in a well known manner shift the contact fingers of the reverser to the right hand contact strips, the connections being analogous to those existing when the controller G was on the pole G^1 . 55 It will be seen however that the two armature circuits have been reversed, causing the motors to rotate in the opposite direction. The switches S^1 to S^4 operate as in Fig. 1.

60 Referring now to Fig. 3, I have shown the reversing mechanism of Fig. 1 with the rheo-

stat switches S^1 to S^4 of Patent No. 793,570, granted to Arthur C. Eastwood, the switch solenoids being all connected in series between one of the auxiliary contacts of the switch S^8 and the contact of the relay switch 70 C^2 and being wound with a different number of turns as described in said patent.

The operation of the mechanism of Fig. 3 will be plain from Fig. 1 and said patent. In this mechanism the speed of the motor is controlled by the small auxiliary series motor M^2 in series with the single wire connecting the master-controller G to the magnet C^1 . Different speeds are obtained at different predetermined positions of the handle G , as stated in 80 said Patent No. 793,570.

Referring to Fig. 4, I show a system where in the reversing switches S^6 to S^8 are as in Figs. 1 and 3, and the switches S^1 to S^4 are connected somewhat like those of Fig. 1. 85 Instead of the positive pole of the switch B being connected to one of each of the auxiliary contacts of the switches S^1 to S^4 as in Fig. 1, this pole is in Fig. 4 connected to the relay switches E^1 , E^2 , E^3 , and E^4 , whose fixed contacts except that of S^1 are connected to one of the auxiliary contacts of the preceding switch, the contact of switch E^1 being connected to the solenoid of the switch S^1 .

The relay magnets D^1 to D^4 , controlling the 95 respective switches E^1 to E^4 , are connected in series between one of the auxiliary contacts of the switches S^7 and S^8 on the one hand and the contact of the switch C^2 of the relay magnet C^1 , whose winding has one end connected 100 as in Fig. 1 and the other end as in Fig. 3.

The motor circuits are as in Fig. 1. The master-controller circuit is the same as in Fig. 1 except that the upper auxiliary contact of the switch S^8 does not lead to the 105 solenoid of the switch S^1 , but to the negative line, to which also the said solenoid is also connected. In Fig. 4 the solenoid of the switch S^4 is controlled by the switch E^1 and is energized as long as current is passing 110 through the controller G . After the switch E^1 is closed, the switch S^1 closes, its auxiliary contacts connecting in circuit the solenoid of the succeeding rheostat switch S^2 , which will close as soon as the handle G has been moved 115 sufficiently to cause the current strength through the motor M^2 to increase enough to energize the relay D^2 to close the switch E^2 . The switches S^3 and S^4 are likewise controlled by the relay switches E^3 and E^4 , respectively, 120 whose actuation also depends upon the position of the handle G and consequently the strength of the current passing through the motor M^2 . I have shown the relay magnets D^1 to D^4 with successively larger weights at 125 one end to govern the sequence of the closing of the switches E^1 to E^4 , but other means for causing the successive closing of these switches may be adopted.

Referring now to Fig. 5, I show a con- 130

troller system, adapted to control a number of motors from a single point, for example, in the case of a multiple unit train.

Fig. 5 shows a train of three units, each being substantially like that of Fig. 3, the separate units being connected in series by single wires and the master-controller being connected to one of the magnetic or reversing controllers by only a single wire.

10 The switches S^1 to S^4 and their connections are as in Fig. 3 except that the positive and negative mains passing through the switch B of Fig. 3 are connected in Fig. 5 with the trolley or shoe W , and ground T , 15 the poles of the master-controller or switch G being also connected to the said mains.

The windings of the relay C^3 are placed in series with the master-controller G and control the two relay switches C^2 and C^4 . The 20 relay switch C^2 of the relay C^3 is when closed in a circuit leading from the said controller to the winding of the relay C^3 of the next succeeding unit and the relay switch C^4 is when closed in a circuit leading from said controller to the solenoids, or electro-magnetic controlling mechanism, of the resistance switches S^1 to S^4 . The single wire leading from the first to the second unit has the same function to the second unit as the single master-controller wire has to the first unit. The third unit is connected to the second unit the same as the first and second units are connected and so on with all succeeding units.

35 When the windings of the relay C^3 are energized, its switches C^2 and C^4 are closed in an obvious manner, so that the master-controller current is transmitted to all the units in the train, each unit acting as if it had independent connection with the master-controller.

If the handle G be thrown to the positive pole G^3 , the current passes from the trolley-wire or third rail through the trolley or shoe W , the handle G , the series motor M^2 , the windings of the relay C^3 and its switch C^4 , through the reversing and resistance controlling mechanism of the first unit as in Fig. 3 to the negative at the ground T . By the 45 closing of the switches C^2 and C^4 , the reversing and resistance mechanisms of all units are started simultaneously, the position of the handle G providing means for controlling simultaneously the speed of all the motors M . 50 The movement of the handle to off-position or to the negative pole G^4 has evidently the same operation on each unit as it has in Fig. 3.

It is clear that the mechanism of Fig. 2 could be substituted for that shown in each 55 unit on Fig. 5.

Referring now to Fig. 6, I have shown my system of motor control applied to the system shown and described in Patent No. 793,514, granted to Arthur C. Eastwood.

60 The reference letters used on Fig. 6 are so

far as they are used the same as on the drawings of Eastwood's said patent, No. 793,514, except G^6 on this figure represents the solenoid G on the drawings of the patent.

Two relays m^1 and m^2 are so constructed, as 70 by a different number of turns in the windings thereof, that m^2 will close its switch n^2 at a smaller current than m^1 will close its switch n^1 , which windings are in series between the master-controller and a point between the 75 windings of the magnets d and d^1 which operate the reversing switch having the fixed contacts b and the movable contacts b^1 and b^2 , as described in said patent, No. 793,514.

The solenoid winding G^5 is connected to 80 the fixed contact of the switch n^2 of the relay m^2 and the solenoid F is connected to the fixed contact of the switch n^1 of the relay m^1 . The solenoids d and d^1 are in series between the positive main and a point between the 85 solenoid F and the connection of the latter with the switch-controller E .

The positive and negative mains are connected directly to the contacts i^1 and i^2 , and the contacts h^7 are connected to the relay 90 winding m^1 .

I have provided contacts h^8 alternating with the contacts h^7 and connected also to the relay winding m^1 , a resistance r being inserted in the circuit of the contacts h^8 to reduce the current through the contacts h^8 to 95 such an amount as to cause the relay m^1 to open its switch n^1 , while retaining the switch n^2 closed.

If the master-controller be operated to 100 move the contacts i^5 upon the contacts i^2 and i^3 and the slider h^3 be then lowered so as to bridge the contact plate h^6 alternately with the contacts h^7 and h^8 , the current will flow from the positive main through the solenoid 105 d^1 , the relay windings m^1 and m^2 , the contacts h^7 and h^8 alternately, the slider h^3 , the contacts h^6 , i^2 , i^5 , and i^3 to the negative main. This circuit actuates the solenoid d^1 to close the contacts b^1 on the contacts b . The motor circuit is now closed through all the 110 resistance in the controller E , as in said patent, and is from the positive main through the upper pair of contacts, b , b^1 of the reversing switch, the armature a , the lower pairs of 115 contacts b , b^1 , the field winding a^1 , and the resistance controller E to the negative main.

During the falling of the slider h^3 , circuit 120 through the switch n^1 has been interrupted several times by the slider as it engages with the contacts h^8 , whereby the current from the positive main passes through the solenoid F in impulses, which operate the magnetic resistance controller E as described in said Patent No. 793,514.

As the slider makes and breaks the circuit through relay winding m^1 , the current through the solenoid G^6 actuates the solenoid G^5 as the solenoid G of said patent is actuated.

When the master-controller is thrown to 130

off-position, the relays m^1 , m^2 and the solenoids d^1 , F and G^5 , and the winding e are all de-energized and the motor circuit is opened on the magnetic controller. The reversing 5 switch remains inactive, because its actuating solenoids are both in a permanent bridge across the line, as in all the forms of my invention, so that no blow-out magnets are needed for the reversing switch.

10 If the contacts i^5 are now placed on the contacts i and i^2 and the slider again lowered, the current will flow from the positive main through contacts i^1 , i^5 , i , and h^6 , the slider h^3 , the contacts h^7 and h^8 , the relay windings m^1 and m^2 , and the solenoid d to the negative main. The solenoid d will now cause the reversing controller to shift so as to bring the contacts b^2 on the contacts b . This causes the current to be reversed through the armature a owing to the fact that the contacts b^2 are connected alternately into pairs instead of consecutively as with the contacts b^1 . The remaining parts of the apparatus work as when the contacts i^2 and i^5 are bridged.

25 Referring now to Fig. 7, I have shown a multiple unit system, wherein the units are, except as hereinafter stated, the same as shown in Fig. 6, the motor circuits being omitted. The reference letters are the same as on Fig. 6 so far as applicable. In Fig. 7 the relay winding m^2 controls two pairs of contacts n^3 and n^4 , instead of one contact as in Fig. 6. The contacts n^4 when bridged by the switch n^5 , connect the winding m^2 and the master-controller circuit in series with the next succeeding unit, instead of with the negative main, as in Fig. 6. The master-controller circuit through the winding m^2 of the last unit is led to the ground or a negative return. The wire leading from one unit to another unit is derived from a point between the two windings m^1 and m^2 and passes through the contacts n^4 to the winding m^2 of the succeeding unit. The contacts n^3 have the same function as the fixed contact of the switch n^2 of Fig. 6.

The contacts n^3 when bridged connect the solenoid G^5 to the positive main, as does the switch n^2 in Fig. 6.

50 It is to be understood that the drawings are merely illustrative of a few ways, in which my invention can be practiced, but it is intended to include within the scope of my invention all apparatus which embodies the principles thereof. While the drawings have shown definite connections and arrangements, persons skilled in the art will readily make minor changes without materially altering the principles involved.

60 I claim—

1. In a system for controlling motor the combination of a master-controller, motor reversing mechanism governed thereby, a single conductor connecting said master-controller and said reversing mechanism, a

resistance controlling switch, an electromagnet having its winding in series with said conductor, and a circuit controlled by said magnet to control said resistance controlling switch.

2. In a system for controlling motors, the combination of a reversing switch, electromagnets for operating the same, a resistance switch, an electro-magnet for operating the same, a master-controller, a single conductor from the master-controller to first electromagnets, a relay in series with the single conductor, the relay switch, on energization of the relay magnet, being connected in circuit with said conductor, and means for preventing the operation of the reversing switch when the master-controller is thrown to off-position.

3. In a system for controlling motors, the combination of a reversing switch, electro-magnetic mechanism for operating the same, a plurality of resistance switches, electro-magnetic mechanism for operating the same, a master-controller connected to the electromagnets of the said mechanisms, means for preventing the operation of the reversing switch when the master-controller is thrown to off-position, means for deenergizing the electro-magnets of the resistance switches when said controller is thrown to off-position, and a blow-out magnet for one of said resistance switches, the connections being such that the motor circuit is always opened at the switch having said blow-out magnet.

4. In a system for controlling motors, the combination of a plurality of motor units, each including a motor reversing mechanism, a speed-controlling mechanism and a master-controller, a single conductor between the said controller and the reversing and speed-controlling mechanism of the first unit, and a single conductor to connect each unit to the reversing mechanism of the succeeding unit.

5. In a system for controlling motors, the combination of a plurality of motor units, a pair of relay switches and a reversing mechanism in each unit, and a master-controller connected to the reversing mechanism of the first unit and the relay windings of the first unit, one relay switch in each unit controlling the resistance switches of the unit to which it belongs and the other relay switch connecting the unit to which it belongs to the succeeding unit.

6. In a system for controlling motors, the combination of a plurality of motor units, a pair of relay switches in each unit, and a master-controller connected with the relay windings of the first unit, one relay switch in each unit controlling the resistance switches of the unit to which it belongs and the other relay switch connecting the unit to which it belongs with the relay switch operating mechanism of the succeeding unit.

7. In a system for controlling motors, the combination of a plurality of motor units, a pair of switches and a motor reversing device in each unit, electro-magnetic mechanism for operating said switches, and a master-controller connected with the said mechanism of the first unit, one of the switches controlling the resistance switches of the unit to which it belongs, and the other switch con-

trolling the electro-magnetic mechanism of 10 the succeeding unit.

Signed at Cleveland O., this 24th day of February, 1906.

JAY H. HALL.
